UNITED STATES PATENT OFFICE

CECIL GEORGE QUICK, OF ELTHAM, LONDON, AND THOMAS RICHARD BENNETT, OF WILLESDEN, LONDON, ENGLAND, ASSIGNORS TO R. HOE & CO., INC., OF NEW YORK, N. Y., A CORPORATION OF NEW YORK

LATE NEWS DEVICE FOR PRINTING MACHINES

Application filed October 25, 1929, Serial No. 402,501, and in Great Britain November 5, 1928.

This invention relates to late news printing devices used on rotary newspaper printing machines.

The object of the present invention is to provide a late news printing apparatus, the form cylinder of which can readily be turned to a convenient position to change the late news printing form without moving the main printing cylinders.

According to the present invention there is provided in combination with an impression cylinder, one or more late news form cylinders each of which are adapted to receive one or more fudge boxes, and to cooperate with the impression cylinder. Means are also provided for driving the said form cylinder in synchronism with the impression cylinder, means for moving said form cylinder and impression cylinder into and out of impression relation with each other, for connecting and disconnecting the form cylinder to and from the driving means.

Means are provided for rotating the late news form cylinder when this latter is moved out of impression and driving connection, for moving the said cylinder into convenient positions for the loading, removal and replacement of the various fudge boxes.

The invention is illustrated in the accompanying drawings in which Figure 1 is a view partly in section showing the late news device, and a portion of the printing machine as viewed from the side of the machine;

Figure 2 is a plan view drawn to a smaller scale, showing the mechanism as viewed in the direction of arrow 2 of Figure 1;

Figure 3 is a view mostly in section, showing the clutch mechanism as seen in the direction of arrow 3, of Figure 2, the parts in section being as viewed on the line A—A of Figure 2;

Figure 4 is a view of the mechanism for moving the late news form cylinders into and out of impression relation, the view being shown as seen in the direction of the arrow 4, of Figure 1;

Figure 5 is a diagrammatic view showing the late news form cylinder in impression relation with the impression cylinder, and in contact with the inking mechanism; and

Figure 6 is a diagrammatic view similar to Figure 5, but showing the late news form cylinder moved out of impression relation.

In the drawings, 1 and 2 indicate two late news form cylinders secured to shaft 3, which is parallel with the axis of an impression cylinder 4 and is mounted in eccentric bearing bushings 5, rotatably supported in the frame 6 of the machine; one of the bushings 5 being provided at each end of the shaft 3, and one intermediate its ends. The bushings are each formed or provided with teeth 7, which mesh with the teeth of quadrant gears 8, fastened to a shaft 9, that is rotatably supported parallel to the shaft 3.

Fastened to the shaft 9, at a point adjacent to the central bushing is an arm 10, slotted for the reception of a block 11, that is screw threaded to receive an adjusting bolt 12, which is rotatably but not slidably mounted in the end walls of the slot. The position of the block 11 in the slot, is capable thereby of adjustment, and provides means for adjustment between the late news form cylinders 1, 2 and the impression cylinder 4, that is independent of the throw off mechanism hereinafter described.

Pivotedly mounted at one end of a pin 13, carried by a block 11, is a link 14, the other end of which is pivotally connected to an arm 15 fastened to a short shaft 16, to which an operating arm 17 is secured. The extreme positions of the arm 17 are limited by pins 18 on the frame that are adapted to engage a lug 19, formed on the arm 17.

On one end of the shaft 3, is provided a manually operable clutch 20, that may have a pin 20' and be operated by a hand lever 21, for connecting or disconnecting the shaft 3, to and from a gear wheel 22, that is recessed to form a seat for the pin 20' and is loosely mounted on the shaft 3. The gear 22 is in mesh with the flanged gear 23, which is secured to the shaft of impression cylinder 4. The clutch member 20 slides on a feather 3' on the shaft 3, and the lever 21 is secured to a shaft "S" which turns in the bracket "B" and carries a pin 21' which engages the groove G in the clutch member 20.

At the other end of the shaft 3, there is

provided an inching mechanism comprising a ratchet wheel 24, secured to the shaft 3, and engaged by a pawl 25, pivotally mounted on an operating lever 26.

5 The late news cylinders are inked by an inking roller 27, in contact with an ink cylinder 28, that is engaged by the usual distributing rollers 29 and supplied with ink by a ductor roller 30, from a fountain roller 31.

10 **The flange on the gear 23 engages the sides of the gear 22 and holds it in position on the shaft when the clutch is released. Gear 23 meshes with gear 22, that is secured to a running shaft of the machine thus providing a 15 means for driving the late news form cylinder.**

If desired an additional late news device may be arranged to operate in connection with the impression cylinder 4. Such an arrangement is shown in outline in Figure 1, wherein the cylinder 33, corresponds with cylinder 1, roller 34 with roller 27, ink cylinder 35 with 28, and rollers 36, 37 and 38 respectively with rollers 29, 30 and 31.

20 **25 In operation, when it is desired to change the fudge boxes on either of the late news cylinders or alter the type therein, the operating arm 17 is rocked to rotate the eccentric bushings 5, through the quadrant 8 and gear 7; the bushings being so arranged as to move the late news cylinders 1 and 2, out of operating engagement with the impression cylinder 4, and the inking roller 27, as shown in Figure 6.**

30 **35 The clutch 20 is then operated to disconnect the shaft 3 from the gear 22, and the apparatus is then ready for the attachment or removal of the fudge boxes, or any desired alteration of the late news form. When 40 more than one fudge box is used on the late news cylinders, after the first one has been attached or removed, the cylinders are rotated to bring them into a convenient position for attaching or removing another fudge 45 box, by rocking the "inch" lever 26, this being easily effected by hand since the shaft 3 is disconnected from its driving mechanism.**

50 **55 When the fudge boxes have been attached or removed and replaced, the pin clutch 20 is actuated to connect the shaft 3 to the gear 22 and the operating lever 17 is rocked to cause the eccentric bushings 5 to move the late news cylinders 1 and 2 in to contact with the impression cylinder 4, and with the inking rollers 27, as shown in Figures 1 and 5.**

60 **It will be seen that with an apparatus made in accordance with this invention, a simple arrangement is provided for loading or removing and replacing fudge boxes without "inch"ing the whole machine, and that access to all parts of the late news cylinders may be had without the necessity for moving the main printing cylinders.**

65 **65 It will be understood that instead of the**

fudge boxes referred to herein that are used to hold type slugs, that the invention is equally adaptable to the form of late news device in which stereotype plates replace the fudge boxes.

70 **What we claim is:**

1. In a late news device for printing machines, an impression cylinder, a late news form cylinder, adapted to cooperate with said impression cylinder, means for connecting and disconnecting said form cylinder to and from a driving means therefor, means for moving said form cylinder and said impression cylinder relatively to one another into and out of impression relation, and means for rotating the late news form cylinder while it is disconnected from the driving means.

75 2. In a late news device for a printing machine, an impression cylinder, an inking mechanism, a late news form cylinder adapted to cooperate with the impression cylinder and with the inking mechanism, means for connecting and disconnecting said form cylinder to and from a driving means therefor, means for moving said form cylinder into and out of cooperative relation to the inking mechanism and the impression cylinder, and means for rotating the late news form cylinder when it has been disconnected from the driving means.

80 3. In a late news device for printing machines, an impression cylinder, an inking mechanism, a late news form cylinder in operating engagement with the inking mechanism and the impression cylinder, means for driving the form cylinder in synchronism with the impression cylinder, means for disconnecting the form cylinder from its drive, means for moving the form cylinder out of operating engagement with the impression cylinder and the ink mechanism, and manually operated means for rotating the form cylinder while it is disconnected.

85 4. In a late news device for printing machines, an impression cylinder, an inking mechanism, a plurality of late news form cylinders simultaneously in operating engagement with the inking mechanism and the impression cylinder, means for driving the form cylinders in synchronism with the impression cylinder, means for simultaneously disconnecting the form cylinders from their driving mechanism, means for moving the form cylinders out of operating engagement with the impression cylinder and the inking mechanism, and manually operated means for rotating the form cylinders while they are disconnected.

90 5. In a late news device for printing machines, an impression cylinder, an inking mechanism, a late news form cylinder in operating engagement with the inking mechanism and the impression cylinder, means for driving the form cylinder in syn-

chronism with the impression cylinder; means for disconnecting the form cylinder from its driving mechanism; means for moving the form cylinder out of operating engagement with the impression cylinder and the inking mechanism, including eccentric bearings supporting the late news cylinder, said bearings being arranged with teeth in mesh with a toothed member, and an operating lever connected by a link with said toothed member; and manually operated means for rotating the form cylinder while it is disconnected.

In testimony whereof, we affix our signatures.
